DESIGN FOR A BRASSIÈRE OR SIMILAR ARTICLE

George A. Kaufmann, Essex Feils, N. J., assignor
to The H & W Company, Inc., Newark, N. J., a corporation of New Jersey

Application May 31, 1939, Serial No. 85,259

Term of patent 7 years

To all whom it may concern:

Be it known that I, George A. Kaufmann, a citizen of the United States, residing at Essex Feils, county of Essex, State of New Jersey, have invented a new, original, and ornamental Design for a Brassière or Similar Article, of which the following is a specification, reference being had to the accompanying drawing, forming a part thereof,

Fig. 1 is a front view of a brassière showing my new design;

Fig. 2 is a back view of the same; and

Fig. 3 is a perspective of the same.

I claim:

The ornamental design for a brassière or similar article, as shown.

GEORGE A. KAUFMANN.
